UNITED STATES PATENT OFFICE

SHERMAN G. LONG, OF PEORIA, ILLINOIS

DESIGN FOR A CAN OR SIMILAR RECEPTACLE

Application filed November 17, 1930. Serial No. 37,686. Term of patent 14 years.

To all whom it may concern:

Be it known that I, SHERMAN G. LONG, a citizen of the United States, residing at Peoria, in the county of Peoria and State of Illinois, have invented a new, original, and ornamental Design for a Can or Similar Receptacle, of which the following is a specification, reference being had to the accompanying drawing, forming a part thereof, wherein—

Fig. 1 is a side elevation; and
Fig. 2 is a top plan.

What I claim is:
The ornamental design for a can or similar receptacle, as shown.

SHERMAN G. LONG.
